(57) **CLAIM**

The ornamental design for a rolled paper product as shown
and described.

DESCRIPTION

FIG. 1 is a perspective view of a rolled paper product
according to our new design;

FIG. 2 is a top plan view thereof;

FIG. 3 is a rear plan view thereof;

FIG. 4 is a side elevation view thereof;

FIG. 5 is the other side elevation view thereof;

FIG. 6 is a top view thereof; and,

FIG. 7 is a bottom view thereof.

The broken lines and areas within them depict portions of
the rolled paper product that form no part of the claimed
design.

1 Claim, 7 Drawing Sheets
